A. BUTTERWORTH.
METHOD FOR SOAPING CLOTH.
APPLICATION FILED AUG. 18, 1916.

1,235,183.

Patented July 31, 1917

Inventor:
Arthur Butterworth

by George W. Ramsey, atty.

UNITED STATES PATENT OFFICE.

ARTHUR BUTTERWORTH, OF WILTON, NEW HAMPSHIRE.

METHOD FOR SOAPING CLOTH.

1,235,183.

Specification of Letters Patent.

Patented July 31, 1917.

Application filed August 18, 1916. Serial No. 115,684.

To all whom it may concern:

Be it known that I, ARTHUR BUTTERWORTH, a subject of the King of England, and a resident of the town of Wilton, in the county of Hillsborough, State of New Hampshire, have invented certain new and useful Improvements in Methods for Soaping Cloth, of which the following is a specification.

10 This invention relates broadly to textiles, and more particularly in applying to woolen cloth soap necessary for the fulling operation.

15 The principal object of the present invention resides in the method of preparing, transporting, and applying liquid soap necessary to the fulling process of woolen cloth.

20 Another and a primary object of the present invention is the production of a machine for carrying out the method previously specified.

25 A more specific object of the present invention comprises the method of breaking up and aerating liquid soap; then transporting the liquid mass to the place of use; then spreading the liquid evenly over the cloth to be soaped.

30 A still further and more specific object of the present invention comprises the production of a machine including a supply reservoir for liquid soap, an agitator and conveyer for removing the soap from the supply hopper, a suitable pump for providing pressure to drive the liquid soap through suitable conduits, and a suitable nozzle for spreading the soap over the cloth to be soaped.

35 Other and further objects of the present invention will in part be obvious and will in part be pointed out hereinafter by reference to the accompanying drawings forming a part of this application, and wherein like characters are used to represent like parts throughout the several views thereof.

40 Figure 1 is a view illustrating one form of apparatus for carrying out my invention.

45 Fig. 2 is a more or less diagrammatical view illustrating one manner of carrying out my invention.

50 Fig. 3 is a diagrammatic view showing one manner of arranging the apparatus.

After woolen cloth is woven one of the finishing processes includes fulling. To carry out the fulling process successfully

pressure, heat, and moisture are elements 55 to be considered. The moisture is usually provided in the form of liquid soap, which in most cases comprises a stiff jelly-like substance that is chopped into masses with an ordinary garden hoe and then carried in 60 pails to the fulling machine where it is poured on the cloth and spread out thereon.

Usually the fulling machines are some distance from the place where the liquid soap is made so that considerable labor is 65 required to transport the soap. Furthermore, by this old way of applying the soap it is substantially impossible to spread the soap evenly over the cloth.

The present invention may be embodied in 70 a machine including an agitator and a pump together with suitable conduits leading to the fulling machines and provided with a spreading nozzle of any desired character.

For convenience, the agitator and the 75 pump may be located adjacent the soap tank, thereby avoiding the necessity of transporting the soap for any considerable distance. The liquid soap reservoir connected to the pump preferably comprises a hopper 80 which terminates at the bottom of a vertical tube that leads to a suitable pump mechanism. An agitator, preferably in the form of a screw conveyer, is provided in this vertical pipe and by means of this screw 85 conveyer the liquid soap is broken up, made more fluid, and at the same time is carried forward to the pump. The rapid revolution of the pump still further breaks up the liquid soap and by the time the soap leaves 90 the pump it is in the form of a thick lather. This thick lather may be conveyed through the conduits as specified and the lather is applied to the cloth in the fulling machine. It may be convenient to utilize a spreading 95 nozzle for this purpose and a suitable form of such nozzle may be provided by a perforated pipe connected to the end of the conduit.

Referring now to the drawings, and more 100 particularly to Fig. 1, a suitable hopper 1 may be mounted upon a base plate 2 and may be suitably secured thereto by means of braces 4. This hopper 1 terminates at its lower portion in a cylindrical conduit 105 5 in which is provided a screw conveyer or agitator 6 that is mounted upon a shaft 7 journaled in a bracket 8 carried upon the

upper part of the hopper 1. This vertical shaft 7 carries at its upper end a bevel or miter gear 9 which engages a similar bevel gear 10 that is carried by the drive shaft 5 11 which is journaled in the bracket 12.

The cylindrical conduit 5 is connected by suitable piping 14 to the inlet side of a pump 15. I have illustrated a rotary force pump as the preferred form, but I desire 10 it to be understood that any type of pump, preferably rotary pump, may be suitable for the purpose of carrying out my invention.

The outlet side of this pump 15 is connected by suitable conduits 16 with nozzles 15 17 located over the path of the cloth in the fulling machines. In order to suitably regulate the spreading of the aerated or liquid soap valves 18 are provided adjacent each of the spreading nozzles 17. These valves may 20 be of any convenient type which allows a full flow of the soap to the spreading nozzles. In order to prevent excessive and dangerous back pressure in the pump, should all of the valves 18 connected with the main 25 line 16 be simultaneously closed, a relief valve 19 is provided in the conduit 20 which leads from one side of the outlet of the pump to the reservoir hopper 1. The relief valve 19 is spring controlled and is adjustable in order to maintain sufficient pressure 30 in the main line 16 to insure delivery of the soap to the most distant point of application.

In Fig. 2 of the drawings is diagrammatically illustrated the apparatus including the distributing and aerating mechanism indicated as A, and the operative portions of the fulling machine as indicated at B. In this diagrammatic illustration the fulling 40 machine is disclosed as including pressure rollers 21 and 22 together with a guide 24 in front of the pressure rollers and a trap or crimping box 25 in the rear thereof. The cloth 26 is illustrated as passing through the 45 guide 24, the pressure rollers 21 and 22, and the crimping box 25. The spreading nozzle 17, it will be noted, is arranged over the cloth on the intake side of the pressure rollers so that liquid soap is evenly deposited 50 as at 27 on the cloth prior to its passage through the said pressure rollers. The fulling machine parts previously specified are all old in the art and the present invention does not contemplate a reorganization of the 55 fulling machine other than providing the suitable pipes and nozzles necessary to con-

duct and distribute the liquid soap as is above specified.

The action of the rotary pump breaks up the soap into a thick creamy substance or lather, as has been previously explained, and this substance or lather is maintained under pressure due to the resistance of flow in the distributing hose and also to resistance caused by the restriction at the nozzle of the hose, and this resistance maintains the air, in the lather or soap, trapped, until the lather is emitted from the spreading nozzle. This has the effect of causing the soap to spread and expand more evenly over the cloth where it is being applied.

Realizing that it is possible to vary the physical embodiments of the apparatus included in my invention without departing from the scope of the invention, I desire it 75 to be understood that the specific mechanism herein shown shall be understood as illustrative and not in the limiting sense.

Having thus described my invention what I claim is:—

1. The method of applying fluid soap to cloth and the like, which method comprises agitating the soap to be applied to produce a thick, creamy lather; maintaining the agitated soap in lather form under pressure and 85 out of contact with the atmosphere; conducting the lather so maintained to the place of application; and then relieving the pressure and spreading the soap over the cloth.

2. The method of applying liquid soap for fulling cloth, which method comprises agitating the soap sufficiently to produce a thick creamy lather; then conducting the lather under pressure to the place of application; then releasing the pressure and 95 spreading the lather over the cloth.

3. The method of applying fluid soap for fulling cloth, which method comprises agitating the soap to form a thick creamy lather; conducting the lather to the point 100 of application; then spreading the lather over the cloth prior to passage of the cloth through the pressure rolls of a fulling machine.

4. The method of fulling cloth which consists in supplying liquid soap in lather form thereto under pressure, releasing the pressure and evenly distributing the lather over the cloth, and then subjecting the cloth to pressure, substantially as described.

ARTHUR BUTTERWORTH
